UNITED STATES PATENT OFFICE.

ELISHA H. SHEPARD, OF BOYNE CITY, MICHIGAN, ASSIGNOR OF ONE-HALF TO ISAAC N.
CONRAD AND ANNIE C. CONRAD, OF BOYNE CITY, MICHIGAN.

RAIL-JOINT.

1,020,317.

Specification of Letters Patent. Patented Mar. 12, 1912.

Application filed June 15, 1911. Serial No. 633,269.

To all whom it may concern:

Be it known that I, ELISHA H. SHEPARD, a citizen of the United States, residing at Boyne City, in the county of Charlevoix and State of Michigan, have invented certain new and useful Improvements in Rail-Joints, of which the following is a specification.

This invention relates to rail-joints, and particularly to fastening devices for uniting the meeting ends of railway rails, the object of the invention being to provide simple, cheap and effective means for use in place of the ordinary bolts and nuts and in connection with ordinary fish-plates, whereby the rails may be quickly, firmly and securely joined in such manner as to permit free expansion and contraction of the rails, while at the same time admitting of their ready and convenient disconnection when occasion requires.

A further object of the invention is to provide fasteners which facilitate the connection and disconnection of the rails and which cannot possibly become casually detached in service.

The invention consists of the features of construction, combination and arrangement of parts, hereinafter fully described and claimed, reference being had to the accompanying drawings, in which:

Figure 1 is a view in side elevation of the meeting ends of two adjoining rails connected by my improved fastening means. Fig. 2 is a top plan view of the same. Fig. 3 is a horizontal transverse section taken in the plane of the fastening means, indicating in dotted lines one of the locking cams in position for locking action or release. Figs. 4, 5 and 6 are views of the bolt, cam and spring of one of the sets of fasteners.

Referring to the drawings, 1 and 2 designate the meeting ends of adjoining rails, and 3 and 4 fish-plates of ordinary construction, bearing against opposite sides of the webs of the rails, the webs and fish-plates being provided with the usual elongated openings for the passage of the fastening-bolts.

Arranged to bear against the outer fish-plate 4 are longitudinally bowed spring plates 5, each provided with an elongated opening 6. Through the openings in the rail webs, fish-plates and bowed spring plates pass bolts or keys 7, each having a flat rectangular body or shank adapted to

slide longitudinally in the openings to permit expansion and retraction of the joint, while held from turning movement in the openings. Each key or bolt is formed at one end with a head 8 bearing against the inner fish-plate 3, and has a hooked outer end 9 projecting beyond the outer fish-plate 4, the bill of the hook extending laterally from the bolt substantially parallel with the line of the rails.

Engaging the hooked ends of each bolt is a cam latch or locking device 10, said device comprising a longitudinally tapered body having a substantially flat outer side 11 and a curved inner side 12, the latter being adapted to bear upon the convex face of the associated spring plate 5 when the said locking device is in locking position. The outer or reduced end 13 of the locking device forms a handle or manipulating portion, and at its inner end said device is provided with a cross piece or journal 14, of substantially cylindrical form to pivotally engage the hook 9 of the locking bolt. The cam is provided with a slot 15 for the reception and passage of the hook, and is formed on opposite sides of said slot with inclined or cam surfaces 16 extending to the inner end of the cam, at which point the cam is rounded to give the proper contour to the journal and to form a bearing face 17. The cam surfaces are provided upon base flanges or check plates 18, which are adapted to engage opposite faces of the bolt when the cam is applied, to facilitate the application of the cam to the bolt.

After each bolt is passed through the rails and fish-plates, the bowed spring plate 5 is fitted upon the hooked end of the bolt so that its concave surface faces the fish-plate 4 and said spring plate bears terminally on said fish-plate. The cam locking device is then arranged in the position shown in dotted lines in Fig. 3 and brought into engagement with the hooked end of the bolt, so that the bill of the hook projects into the slot 15, while the surface 17 of the cam rests upon the spring plate. The cam is then turned by means of a suitable implement to the full line position shown in the drawing, in which it lies parallel with the rails, and its cam surfaces engage and compress the spring plate to a nearly flattened position, whereby the bolt is drawn to clamp the parts tightly together and the cam locking

device is held firmly in locking position. The hooked connection between the cam and bolt, as well as the frictional engagement between the cam and spring plate, is sufficient to hold the cam in locking position against all disturbing forces, and as the spring plate is still permitted to have a slight degree of spring movement it will be apparent that a yielding action is afforded which tends to take up at all times any slight looseness of parts which may possibly exist from wear or other causes. As the openings in the rails, fish-plates and spring plates are of a form to loosely receive the shanks of the bolts, free expansion and contraction, and a necessary adjustment of the parts, is permitted to compensate for climatic changes. By inserting a pinch bar or like tool down between the spring plate and portion 13 of the cam, the latter may be forced outwardly to the dotted line position shown in Fig. 3, to permit of its removal, whenever it is necessary to disconnect the rails for repairs or other purposes. It will be seen that by means of the detachable, pivotal connection between the hooked bolts and locking cams, the foregoing advantages are afforded, thus making the locking devices easy to remove even when the parts are rusted, thus overcoming an objection to the use of ordinary bolts and nuts, which must often be cut off before the rails can be disconnected.

Having thus described the invention, what I claim as new is:

- 35 1. A rail fastener comprising a bolt having a hooked end, and a cam having a detachable, pivotal connection with the hooked end of the bolt.
2. A rail fastening comprising a bolt having a hooked end, and a locking cam formed

with a slot to receive the bill of the hook, and a journal to engage the recess of the hook, and provided with cam surfaces to bind against the fish-plate and draw the bolt into the clamping position.

3. The combination with rails and fish-plates having openings therein, of bolts passing through said openings and having hooked ends, locking cams having a detachable pivotal connection with the hooked ends of the bolts.

4. The combination with rails and fish-plates having openings therein, of bolts passing through said openings and having hooked ends, bowed spring plates fitted upon the hooked ends of the bolts and engaging the adjacent fish-plate, and locking cams having a detachable pivotal connection with the hooked ends of the bolts and bearing upon said spring plates.

5. The combination with rails and fish-plates having openings therein, of bolts passing through said openings and having hooked ends, bowed spring plates fitted upon the hooked ends of the bolts and bearing against the adjacent fish-plate, and cam devices having slots to receive the bills of the hooks and journals to engage and seat within the recesses of the hooks, whereby said cam devices are detachably and pivotally connected with the hooks, said cam devices being provided with cam surfaces binding upon and compressing the spring plates to hold the parts connected.

In testimony whereof I affix my signature in presence of two witnesses.

ELISHA H. SHEPARD.
